ELECTRICALLY CONTROLLED BASEBALL
GAME

Eugene P. Koppin, Belleville, Mich.

Application December 4, 1947, Serial No. 789,631

3 Claims. (Cl. 273—89)

1

The present invention relates to improvement in an electrically controlled baseball game adapted for play by two players.

A primary object of the present invention is to provide an electrically controlled baseball game wherein the simulated position and movement of a base runner may be indicated by the progressive illumination of a series of electric lights arranged along the base lines.

Another object of the present invention is to provide such a baseball game wherein the progressive illumination of the base line lights is under the control of the player representing the batting team and wherein the defensive player may simulate a play at one or more of the bases by selectively illuminating player lights representing defensive players located at the various bases and home plate. Means being provided to maintain or simulate one or more runners on the bases in accordance with conventional baseball rules and to extinguish one or more of the player lights at the bases when the players are "out" in accordance with the rules of the game.

Other objects of this invention will appear in the following description and appended claims, reference being had to the accompanying drawings forming a part of this specification wherein like reference characters designate corresponding parts in the several views.

In the drawings:

Fig. 1 is essentially a top elevation of a baseball game embodying the present invention.

Fig. 2 is essentially a fragmentary enlarged vertical section with the electrical wiring removed, taken in the direction of the arrows along the diagonal line 2—2 of Fig. 1.

Fig. 3 is a schematic wiring diagram of an electrical circuit suitable for use with the present invention.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Briefly, the present invention provides a game which may be played by two opposing players. A slightly inclined table is marked out to simulate a baseball diamond, including a pitcher's mound, batter's box, and first, second, third, and home bases. The ball is pitched from the pitcher's mound by electromagnetic means under the control of the defensive player and rolls toward home plate to an electromagnetically actuated bat under the control of the offensive player. A

2

pair of electric lights, preferably of different colors, are located at each of the bases and may be selectively illuminated by an electrical control circuit under the control of the players to simulate the position of a player or the ball.

The movement or position of a base runner on or between the bases is simulated by a series of electric lights arranged in a row along the base lines between the bases and adapted to be progressively illuminated by means of a commutator under the control of the offensive player representing the batting team. The rate at which the runner is advanced or withdrawn is determined by the rate and direction of rotation of the commutator.

Upon illuminating the light which simulates a batter at home plate, the ball is brought into play by the defensive player who actuates the pitching mechanism and "pitches" a ball toward the bat. As the ball rolls down the inclined table or playing field from the pitcher's mound toward home plate, the offensive player actuates the bat so as to drive the ball into the playing field. The timing of the swing of the bat is under the control of the batter so that skill may be exercised in determining the direction in which the ball is batted.

Immediately upon striking a fair ball, the batter or offensive player operates the commutator to progressively illuminate the series of base line lights from home plate to first base, and thereby to simulate the advance of his runner toward first base. Meanwhile, the ball eventually rolls to its initial position within the pitching mechanism by virtue of the inclined table, indicating that the ball has been fielded and is under the control of the defensive team. It is proposed that the runner may safely advance around the bases until the ball is recovered by the defensive team, i. e., returned to its initial position within the pitching mechanism, at which position the ball closes an electric circuit permitting the defensive player to simulate a play at any of the bases by selectively illuminating one of the defensive lights at the corresponding base.

If the runner reaches first base before the defensive player is enabled to illuminate the first baseman light at first base, the runner is safe at first. The lamp representing the runner will remain illuminated at first base. If the runner attempts to reach second base, as indicated by the progressive illumination of the baseline lights between first and second bases, and the ball is recovered by the defensive team before the runner reaches second base, he may be trapped between first and second bases if the defensive player simulates that the ball is under the control of the first and second basemen by illuminating the de-

fensive lights at first and second bases. The light representing the runner is then extinguished. The home plate light is again illuminated to indicate that a second batter is up, the ball is again pitched, and the game continues essentially in accordance with the rules of conventional baseball. By virtue of the electrical control system and the indication of the position of the runner on or between bases, the essential plays of baseball may be simulated by the game. The versatility of the electrical controls and the discretion permitted the players as to the play to be made provide a game which matches the skill of the opposing players.

Details of a particular embodiment of the present invention are shown by way of example in the drawings and comprise a housing having the square or rectangular plane horizontal base 10, the four vertical sides 11, and being supported by the four legs 12 which are braced by the wire braces 13. A portion of the upper surface of the housing is covered by the horizontal L-shaped shelf 14 which extends along two sides of the housing. The baseball field 15 preferably comprises a transparent plate of glass, Plexiglas, or similar material marked or etched to simulate a baseball field, including home plate and first, second, and third bases, indicated respectively by the characters H, I, II, and III. Base lines 16 are marked on the field 15 between the bases. The pitcher's mound 17 and batter's box 18 are also suitably marked on the field 15.

The field 15 is preferably tilted downward toward home plate H from the diagonally opposite corner so as to provide a gradual downward slope to the field toward home plate along all lines parallel to the diagonal between second and home bases. First and third bases are at the same level. Similarly, all lines parallel to the diagonal joining first and third bases are horizontal. Thus a ball on the field 15, free to roll in any direction, will roll down the incline in a direction parallel to the diagonal joining second and home bases.

Four openings 19 are provided within the field 15 immediately outside the base lines 16. Similar holes 20 are located in the left and right out-fields, and an L-shaped hole 21 is provided at the far center field. It is proposed, according to the rules of the game, that a ball falling through the center portion 19A, 20A, or 21A of one of the openings 19, 20, or 21, respectively, will be indicated as a "fly out." When the ball falls through one of the lateral portions of one of the openings 19, 20, or 21, an "out" is not indicated, but the return of the ball to its starting position within the pitching mechanism is accelerated.

Another opening 22 is centrally located within the pitcher's mound 17 to provide passage for the arcuate pitching tube 23. An L-shaped opening 24 behind home plate is provided for eventually receiving the ball if it does not previously drop through one of the aforesaid openings 19, 20, 21, or 22. The ball in play is maintained within the confines of the field 15 by the rails 25 which support the transparent top 26 covering the entire playing field 15. Above the centerfield opening 21 and located essentially midway between the field 15 and top 26, is an L-shaped trough 27 secured to the supporting sides 25 and representing the bleachers. A ball which is hit and elevated sufficiently to land in the bleachers 27 cannot drop through the opening 21 and may be considered a "home run."

Below the playing field 15 is a basin 28, which

is adapted to catch the ball after it drops through any of the aforesaid openings in the field 15, and is declined toward a ball receiving funnel opening 29 located essentially below the pitcher's mound 17. Thus a ball positioned at any place on the playing field 15 will roll down the inclination thereof. If the ball does not previously fall through one of the openings 19 through 22, it will eventually reach one of the rails 25 running parallel to the first and third base lines 16 to the opening 24. After dropping through the field 15, the ball rolls along the inclined basin 28 to the funnel opening 29 through which it drops to the pitching position within the chamber 33, where the ball, indicated by 34 in Fig. 2, comes to rest in front of the end of the pitching plunger 35 and at the mouth of the lower opening of the pitching tube 23.

The plunger 35 is normally spring-pressed to the left by the coil spring 36 around the leftward end of the plunger 35 and under compression between the flanged plunger head 37 and the plunger supporting bracket 38. The plunger 35 is actuated at the discretion of the player representing the defensive team by an electric solenoid operated mechanism 40, supported on the base 10, and strikes the ball 34 to drive it through the pitching tube 23. The driving stroke of the plunger 35 to the right is limited by contact between the movement limiting stop 39 and the side of the plunger housing 41, which latter, together with the bracket 38, are supported on the housing 40. Also supported on the base 10 is the solenoid actuated batting mechanism 44 which is operated at the discretion of the player representing the batting or offensive team to pivot the upright bat operating shaft 45 and thereby to swing the bat 46 secured to the upper end of the shaft 45.

Operation of the game and control of the play by the opposing players is effected by an electric control circuit shown schematically in Fig. 3. As outlined above, the offensive player may advance his men along the base lines by rotating the manually operated crank 47, which is operatively connected, as for example by a worm-driven connection, with the commutator 48 for rotation thereof. Details of the electrical mechanism, including the commutator 48, the solenoid actuated pitching and batting mechanisms 40 and 44, and their operable mechanical linkages are well known to the art and are accordingly not described in detail herein. Also, for the sake of simplicity and clarity, the electrical wiring of the control circuit is not shown in Figs. 1 and 2.

Power for the electrical control circuit is supplied through the terminals 49 and 50, which may be considered the live lead and the ground respectively for the sake of illustration. The four relays 54A, B, C, and D, are connected in parallel between the ground 50 and the four cam operated switches 56A, B, C, and D respectively by the four electrical conductors 55A, B, C, and D respectively. The switches 56A, B, C, and D are operated in sequence by the four cams 57A, B, C, and D, respectively, carried by the rotatable commutator 48 for rotation therewith.

The cams 57 and corresponding cam switches 56 are shown spaced at different radii from the center of the commutator 48 so that upon counter-clockwise rotation of the commutator 48, for example, cam 57A will close the cam operated switch 56A when rotated to a position of contact therewith, schematically indicated along the vertical downward radius of the cam 48 in Fig. 3.

Upon continued rotation of the cam 48, the cam 57A will ride off the switch 56A, and the latter will open. Upon rotating cam 57A through 90° from its position of contact with the cam switch 56A, the cam 57B will be in position to close the cam switch 56B. Likewise, cam switches 56C and 56D are closed by the cams 57C and 57D upon rotation of the commutator 48 through successive quarter turns. In operation of the game, the commutator 48 may be rotated in either direction at the discretion of the offensive player.

As schematically indicated by the different radial spacings of the four cams 57 and four cam switches 56, the cams 57 are preferably spaced around the periphery of the commutator 48 at different vertical levels. The corresponding cam switches 56 are spaced at corresponding vertical levels. Accordingly, each cam switch 56A, B, C, or D will be tripped and closed only by its respective cam 57A, B, C, or D. As each cam switch 56 is closed in turn, the circuit through the corresponding relay 54 is completed to the power 49, thereby energizing the said relay 54 and closing the associated relay switch 58A, B, C, or D. The closing of each relay switch 58A, B, C, or D, upon energizing the respective relay 54A, B, C, or D, connects the corresponding brush 59A, B, C, or D with the power line 49. The brushes 59A, B, C, and D make electrical contact with the rotating ring conductors 63A, B, C, and D respectively, which are connected by the conductors 64A, B, C, and D respectively with the terminal brushes or contacts 65A, B, C, and D respectively for selectively completing a circuit with one of the plurality of base line electric light terminals 67, uniformly spaced stationarily around the periphery of the commutator 48.

The four ring conductors 63 and their corresponding leads 64 and terminal contacts 65 rotate with the commutator 48. The contacts 65 are spring-pressed toward the terminals 67 so as to progressively contact the latter upon rotation of the commutator 48, and thereby to progressively light the plurality of base and base line lights 69. The base and base line lights 69 are connected with their respective terminals 67 by the plurality of conductors 68, and are grounded to the portion of the lead 50 extended within the diamond formed by the lights 69.

In the present example, fourteen base line lights 69 are evenly distributed along the base line 16 between each pair of the base lights 69H, 69₁, 69₂ and 69₃, making sixty base and base line lights around the periphery of the diamond. Each base light 69H, 69₁, 69₂, and 69₃ is located under its corresponding base, H, I, II, or III. The bases and base lines are preferably stained or etched in the plate 15 so as to be transparent and to permit visibility of the lights 69 when illuminated. As may be seen in Fig. 2, the base and base line lights 69 are supported directly below the base lines 16 by the support 70, which latter is suitably secured to the side portions 11 of the housing.

For the sake of illustration, the uppermost terminal 67H around the commutator 48 may be considered to represent the terminal for the light 69H representing a batter at home plate. When one of the moving contacts 65 is energized and in contact with the terminal 67H, the home base light 69H is illuminated. As the energized terminal 65 rotates clockwise upon rotation of the commutator 48 to the next terminal 67, the next light 69 in the series between home plate and first base is illuminated. Likewise, as the energized

contact 65 moves around the commutator in a clockwise direction, the third, fourth, fifth, and remaining base line lights 69 are progressively illuminated. The fifteenth terminal 67, counting clockwise from 67H, is for the base light 69₁ representing a runner on first base. The next fifteenth terminal is for the base light 69₂ representing a runner on second base, and the next fifteenth terminal 67 is for the base light 69₃ representing a runner on third base. In order to avoid a multiplicity of electrical conductors in the wiring diagram, Fig. 3, the plurality of leads 68 from the terminals 67 on opposite halves of the commutator 48 are shown entering the pair of electrical cables 73 from which the individual leads 68 branch out to their corresponding lights 69.

By way of illustration, the circuit of one of the lights 69 is followed in detail, assuming that the cam 57C has contacted and closed the cam switch 56C, completing the circuit through the relay 54C and thereby closing the normally open relay switch 58C. Closing of the relay switch 58C immediately provides a by-pass circuit from leads 49 to 50 through the relay 54, permitting the cam 57C to ride off and open the cam switch 56C without de-energizing the relay 54C. The circuit through the closed relay switch 58C also energizes the brush 59C and completes an electrical circuit through the ring contact 63C, the conductor 64C, the rotating contact 65C, one of the terminals 67, its associated lead 68 and base or base line light 69, and then to the ground 50.

By the commutator arrangement shown, it is apparent that the offensive player may simulate the advance or retreat of his men along the base lines and from base to base by rotating the commutator 48 so as to progressively light the lights 69. When a runner is put out in accordance with the rules of the game, either at one of the bases or between the bases, the light 69 representing that player is extinguished by means of one of the manually operated normally open switches 74_{1,2,3}. Switch 74₁, for example, is in parallel with the light 69₁, and is adapted upon closing to short out light 69, by connecting the particular lead 68 for the light 69, to the ground 50. When the commutator 48 is moved to position any one of the energized rotating contacts 65 over the terminal 67 for the light 69₁, and switch 74₁ is closed, light 69₁ and likewise the relay 54 through which the light 69, is energized will be shortened by directing the power from line 49, through the appropriate relay switch 58, to ground 50. For example, if the rotating contact 65C is energized and concentrically located over the terminal for the light 69₁, i. e., the fifteenth clockwise terminal 67 after 67H, the current for the light 69₁ will necessarily be supplied through the conductor 64C from the rotating ring contact 63C in contact with the brush 59C, which in turn will be connected through the relay 54C via the relay switch 58C. Closing switch 74₁ in this situation will direct the power from line 49 through relay switch 58C, the brush 59C, ring 63C, conductor 64C, contact 65C, and the lead 68 (which would otherwise energize light 69) and switch 74₁ to the ground 50. Thus electric energy to relay 54C will be shortened to ground 50 and the normally open relay switch 58C will open, de-energizing contact 65C until further rotation of the commutator 48 again closes cam switch 56C. The normally open switches 74₂ and 74₃ are similarly connected to short out the lights 69₂ and 69₃ at second and third bases respectively for de-energizing the contacts 65 which energize these lights.

When the ball 34 is at the pitching position within the chamber 33, it may be "pitched" by closing the manually operated normally open pitching switch 75P which completes a circuit from the power line 49 through the solenoid operated pitching mechanism 40 and to ground 50, driving the plunger 35 to the right in Fig. 2 and pitching the ball through the tube 23, which directs the ball from the pitcher's mound 17 toward home plate H.

As the ball 34 nears the bat 46, the offensive player times its approach and, at the proper instant to bat the ball into the playing field 15, closes the normally open manual switch 76B to complete the circuit from the power line 49 through the solenoid operated batting mechanism 44 to the ground 50, thereby pivoting the shaft 45 and swinging the bat 46.

The ball 34 rolls under its own momentum across the field 15 and may or may not fall into one of the openings 19A, 20A, or 21A. If the ball 34 falls into one of the openings 19A, 20A, or 21A, it closes one of the corresponding switches 77, 78, or 79, schematically indicated somewhat in their proper locations with respect to the field 15, Fig. 3. The ball 34 is preferably an electric conductor, and the switches 77, 78, and 79 are preferably resilient spaced contacts which are momentarily bridged as the ball 34 falls through one of the corresponding openings 19A, 20A, or 21A. As the ball bridges one of the spaced contacts 77, 78, or 79, connected in parallel with each other and the ground 50, and connected in series with the circuit for the fly out light 83 and the power lead 49, the light 83, supported from the support 70 below the transparent field 18, is momentarily illuminated to indicate a fly out.

If the ball does not fall through one of the openings 19A, 20A, or 21A, it may be considered in play until it eventually rolls to its starting position within the chamber 33, whereat it bridges the spaced contacts 84, schematically shown in Fig. 3. At this time, the ball 34 may be considered within the control of the defensive team, since the defensive player may now complete a circuit through one of the normally open manual switches 85_{1,2,3}, H. The switches 85_{1,2,3}, H connect the power line 49 through the bridged contacts 84 to the corner lights 86_{1,2,3}, H, respectively, which may be selectively illuminated to represent the first, second, and third basemen, and catcher, respectively, and which are preferably colored differently from the base and base line lights 69.

By selectively closing one of the switches 85 and illuminating the corresponding defensive player light 86, a play at one of the bases may be simulated. For example, after the batter hits the ball 34 into the playing field 15, the simulated advance of the batter or runner along the base lines is effected by rotating the commutator 48 clockwise. If the ball 34 should be considered a fair hit but should return to the chamber 33 and bridge the terminals 84 before the runner reaches first base, as indicated by the extent of progression of illumination of the base line lights 69, the defensive player may close the switch 85₁ and illuminate the light 86, simulating that the ball 34 has been fielded and thrown to the first baseman, thereby putting the runner out. If the runner should reach first base before the terminals 84 and switch 85₁ are closed, the runner is safe at first. In this instance the first base light 69₁ will be illuminated

and the relay 87₁ in series with the light 69₁ will be energized to open the normally closed relay switch 88₁ in series with the first baseman light 86₁. Thus it will not be possible for the 5 defensive player to make a successful play at first base, by illuminating the first baseman light 86₁, while the runner is safe on first base. Similarly, the relays 87_{2,3} are in series with the base lights 69_{2,3} and are energized to open the normally closed relay switches 88_{2,3} respectively, in series with the second and third baseman lights 86_{2,3} respectively. Accordingly, the second and third basemen lights 86_{2,3} cannot be illuminated while the second and third base lights 69_{2,3} respectively, are illuminated.

It is believed that the operation of the game is quite apparent in view of the above disclosure. The rules of the game may be subject to considerable variation, although it is proposed that the play of the game will be somewhat as follows:

The game is adapted to be played by two opposing players who will follow conventional baseball rules as nearly as practicable. The batter up will be represented by rotating the commutator 48 until one of the contacts 65 is aligned with the terminal 67H. The corresponding cam switch 56 will then be closed and the light 69H will be illuminated. Furthermore, the contact 65 involved will remain energized after opening of the cam switch 56, by virtue of the corresponding holding circuit, from lead 49, through the respective relay switch 58 and relay 54, and to the ground 50, which holding circuit will energize the relay 54 involved until the closing of the proper switch 74. The defensive player then pitches the ball 34 by closing the switch 75P. The offensive player exercises his skill in timing the approach of the ball in an endeavor to bat the ball 34 where desired into the playing field 15. If he makes a fair hit which does not fall into one of the openings 19A, 20A, or 21A, he is credited with a hit and may advance his player along the base lines by rotating the commutator 48 clockwise as rapidly as possible, at the same time keeping his eye upon the ball 34 which is visible through the field 15 even while in the basin 28 below. The offensive player may advance his man as far as he dares without being trapped between bases upon the return of the ball 34 to its initial position within the chamber 33, whereat the contacts 84 are closed to permit the defensive player to make a play at any one or more of the bases.

If for example the first runner reaches first base safely, the first base light 69₁ will be illuminated. Also while the light 69₁ is illuminated, the four rotating contacts 65 will be aligned in contact with the four terminals 67 at the four quarters of the commutator 48, measured from the terminal 67H. Accordingly, the next following contacts 65 will be in contact with the terminal 67H, and the corresponding cam switch 56 will be closed to energize the said contact 65 engaged with the terminal 67H. The illumination of the light 69H will indicate that the second batter is up.

The second batter similarly strives for a hit, and if successful, advances along the base lines by the progression of base line lights 69 upon rotation of the commutator 48. At the same time and at the same rate, the first runner will advance along the base lines from first to second base. If the defensive player is enabled to illuminate the first baseman light 86₁ before the sec-

ond runner reaches first base, the second runner is out. Switch 74₁ is then closed and the light 69 representing the second runner at first base is extinguished by de-energizing the second contact 65 in control of that light. From then on, until the subsequent closing of the appropriate cam switch 56, no base or base line lights 69 will be illuminated through the contact 65 which formerly controlled the simulated position of the second runner. If the first runner has safely reached second base, the second base light 69₂ will be illuminated. Similarly, the light 69H will also be illuminated by the position of the third successive contact 65 to indicate that the third batter is up.

If at any time during the course of the play, a simulated runner is trapped between bases by the simultaneous illumination of the basemen lights 86 behind and ahead of the runner, that runner will be considered out and the light circuit for the base light 69 representing that runner will be broken by opening the proper switch 74 when the contacts 65 are properly aligned at the four quarters of the commutator 48. The commutator 48 may be rotated in either direction so that the men may be advanced or retracted along the base lines at the discretion of the players. It is apparent that most of the actual plays of baseball may be simulated by the controls shown.

Having thus described my invention, I claim:

1. In a baseball game adapted for competitive play by a pair of players and utilizing a ball adapted to roll over a simulated playing field, the combination of a playing board marked to simulate a baseball diamond, a batting mechanism controlled by one player and adapted to bat said ball along the playing field, a pitching mechanism controlled by the other player and adapted to direct the ball toward said batting mechanism, and means controlled by the pair of players for selectively actuating said batting and pitching mechanisms, said playing field being inclined toward the pitching mechanism to return a ball from its position on said board to said pitching mechanism after said ball has been batted by said batting mechanism, said board having base-lines marked on the playing field, a plurality of electric base line lights linearly arranged along said base lines, an electric commutator adapted for reversible operation and operatively connected electrically with said plurality of base line lights for progressively illuminating the latter, and means controlled by the players for regulating the speed and direction of operation of said commutator to simulate the advance or retreat of a runner along said base line, said playing field being provided with a plurality of openings adapted to pass the ball through said board, and having an inclined basin provided below said playing field to return said ball to the pitching position within said pitching mechanism, and a defensive player light positioned at each of the bases of said playing field and means for simulating a defensive play at any one of said bases and including a defensive electric control circuit for selectively illuminating said defensive player lights, and an electric control means at said initial pitching position and operatively connected with said defensive control circuit to prevent operation of the

latter until the return of said balls to said initial pitching position.

2. In a baseball game adapted for competitive play by a pair of players and utilizing a ball adapted to roll over a simulated playing field, the combination of a playing board marked to simulate a baseball diamond, a batting mechanism controlled by one player and adapted to bat the ball along said playing field, means on the playing field adapted to return the ball to an initial position, means controlled by a player adapted to simulate the runner on the baselines of the baseball field and adapted to regulate the speed and direction of the advance or retreat of the runner along the lines, a defensive player light positioned at each of the bases of the playing field, means for simulating a defensive play at any one of the bases and including a defensive electric control circuit for selectively illuminating said defensive player lights, and an electric control means at said initial position and operatively connected with said defensive control circuit to prevent operation of the latter until the return of the ball to said initial position.
- 25 3. In a baseball game adapted for competitive play by a pair of players and utilizing a ball adapted to roll over a simulated playing field, the combination of a playing board marked to simulate a baseball diamond, a batting mechanism controlled by one player and adapted to bat the ball along said playing field, a pitching mechanism controlled by the other player and adapted to direct the ball towards said batting mechanism and means controlled by the pair of players for selectively actuating said batting and pitching mechanism, means positioned on the simulated playing field adapted to return the ball to said pitching mechanism during which time the ball is considered in play, a plurality of electric base line lights linearly arranged along the base lines of the diamond of the playing field and adapted to indicate the progress of a runner moving between the bases and controlled by the players for regulating the speed and direction of the simulated advance or retreat of a runner along the base lines, a defensive player light positioned at each of the bases of the playing field, means for simulating a defensive play at any one of the bases and including a defensive electric control circuit for selectively illuminating said defensive player lights, and an electrically controlled means at said initial pitching position and operatively connected with said defensive control circuit to prevent operation of the latter until the return of said balls to said initial pitching position.
